(57) **CLAIM**

The ornamental design for a rhombus LED module casing, as shown and described.

DESCRIPTION

FIG. 1 is a isometric view of a rhombus LED module casing showing my new design;

FIG. 2 is a top plan view thereof;

FIG. 3 is a bottom plan view thereof;

FIG. 4 is a rear side elevation view thereof;

FIG. 5 is a front side elevation view thereof;

FIG. 6 is a left side elevation view thereof; and,

FIG. 7 is a right side elevation view of thereof.

1 Claim, 3 Drawing Sheets**FIG. 1**

FIG. 2

FIG. 3

FIG. 4

FIG. 5

FIG. 6

FIG. 7
